(57) **CLAIM**

The ornamental design for underwear as shown and described.

DESCRIPTION

FIG. 1 is a perspective view of underwear showing my new design;

FIG. 2 is a front elevational view thereof;

FIG. 3 is a rear elevational view thereof;

FIG. 4 is a left side elevational view thereof; the right side view being the same;

FIG. 5 is another perspective view thereof;

FIG. 6 is a top, front, and left perspective view of the underwear of FIG. 1, shown in a configuration where the modesty flap is torn open; and,

FIG. 7 is a top view of the underwear of FIG. 1, shown open and flattened in a second configuration.

The dash-dash broken lines in the drawings depict the model of the underwear, and these portions do not form part of the claimed design.
